UNITED STATES PATENT OFFICE.

EBER J. HUBBARD, OF BERWYN, ILLINOIS.

SPOOL.

Application filed July 6, 1925. Serial No. 41,457.

My invention relates to spools, particularly spools used in textile mills for supporting yarn, thread, and similar material. The object of the invention is to produce a 5 light weight spool which is stronger and more durable and resistant than the all wood standard spools. In accordance with my invention, the yarn receiving or engaging parts of the spool are of light sheet metal filled 10 and backed by lighter stock, such as wood.

Another object of the invention is to provide improved assembly of the wood filler and backing, and arrangement within the sheet metal shell, so that the resulting structure will be resistant to shocks and bending 15 and will be particularly strong and rigid at the juncture of the core and end flange parts.

On the drawing:

20 Fig. 1 is a plan view, partly in diametral section, of the spool;

Fig. 2 is an end view;

Fig. 3 is an end view of the sheet metal shell before insertion of the wood filler and 25 backing; and

Fig. 4 is a sectional view on plane 4-4 of Fig. 1.

The surface core layer or shell 10 is bent 30 up into cylindrical form from a rectangular piece of sheet metal with its edges intimately connected preferably by means of double seaming 11. Secured to the ends of this cylindrical core shell are the flanges 12 and 13 of cylindric or dish-shaped form and bent 35 integral from sheet metal. Each flange has a central opening 14 of a diameter equal to the inner diameter of the core shell, and in the edges surrounding the opening 14 are the shallow notches 15 through which extend 40 the tongues 16' projecting from the corresponding end of the core shell, these tongues being deflected at right angles and secured, preferably by spot welding, against the inner face of the flange, the ends of the 45 core shell abutting against the outer surface of the flanges around the openings 14. This construction rigidly and securely fixes the flanges relative to the core shell, and holds the flanges tightly against the core ends so 50 that there will be no crevices or openings in which the yarn might catch.

Fitting intimately into each end flange is 55 a filler 16 in the form of a disc of wood, fiber, or other non-metallic light and strong material. The filler is rigidly secured in each flange by spinning the edge section 17

around the outer corner of the filler and a distance into the material, as clearly shown in Fig. 1, this edge section then forming a metallic peripheral seat for the spool which will withstand wear and protect the filler.

The backing inside of the core shell is also of wood or other suitable light and strong material. It comprises two similar parts, each comprising a comparatively thin annular section 18, and a radially contracted end section 19 through which extends the central passageway 20 for receiving the arbor or spindle on which the spool turns when in use or when being wound with 70 yarn. Between the spindle opening 20 and the annular inner end 18 is the conical guide wall 21 for guiding the spindle end to the upper passageway 20 when the spool is applied to a spindle.

At the ends of each backing member is the reduced extension or neck 22 fitting into the central opening 23 through the corresponding flange filler 16. Each flange is secured to its corresponding core backing part by means of the opening 23 and neck 22, which, preferably, have sufficient frictional engagement so that they may be tightly and securely held together, although glue may be used if desired. Before the filler and 80 backing parts are inserted, the flange edges will be straight as indicated in Fig. 3. The backing parts are then inserted from opposite ends into the core shell to bring the flange fillers into the flanges, and the inner ends of the core backing parts will then abut, as shown in Fig. 1. The flange edge sections 17 are then turned over to securely clamp and lock the fillers within the flanges. The inner corners of the flanges are well 85 rounded so that yarn may readily be wound on the spool or unwound therefrom.

In order to accommodate the seam 11 of the core shell, each of the core backing parts has a longitudinal notch 24. The interengagement of the seam and the notches will assist the flange edges 17 in securely holding the metal and wood parts against relative movement.

By intimately engaging and securely connecting together the backing part and the filler part, a rigid low resilient reenforcing structure is provided for the metallic surface or shell parts, and much lighter sheet metal can be used than would otherwise be possible. Non-corrosive sheet metal, such as tin plate is preferably used, the tin plat-

ing affording a very smooth non-friction surface for the yarn.

My improved structure possesses all the advantages of an all metal spool, and possesses the resilient and light weight qualities of the all wood spool. The filling and backing within the sheet metal shell gives the structure resiliency which the all metal spool does not possess.

10 Having described my invention, I claim as follows:—

15 In a spool, the combination of a cylindrical core shell of sheet metal, end structures of sheet metal secured concentrically to the core shell ends, discs of non-metallic filler material secured in said end structures and

having each a central opening, non-metallic backing members fitting in the ends of said core shell and abutting at their inner ends, the outer ends in said backing members 20 having reduced extensions fitting tightly into said filler discs, there being spindle bearing passageways in the outer ends of said backing members, said backing members at their inner ends being of increased internal 25 diameter, and spindle guideways from said backing material inner ends to said spindle passageways.

In witness whereof, I hereunto subscribe my name this 1st day of July, 1925.

EBER J. HUBBARD.
